(57) **CLAIM**

The ornamental design for a case for an electric screwdriver, as shown and described.

DESCRIPTION

FIG. 1 is a first perspective view of a first element of a case for an electric screwdriver showing our new design; FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first embodiment thereof;

FIG. 8 is a bottom view of the first element thereof;

FIG. 9 is a first perspective view of a second element of a case for an electric screwdriver showing our new design; FIG. 10 is a second perspective view of the second element thereof;

FIG. 11 is a front view of the second element thereof;

FIG. 12 is a back view of the second element thereof;

FIG. 13 is a left side view of the second element thereof;

FIG. 14 is a right side view of the second element thereof;

FIG. 15 is a top view of the second embodiment thereof;

FIG. 16 is a bottom view of the second element thereof;

FIG. 17 is a combination view of the first element and the second element of the case for an electric screwdriver thereof; and,

FIG. 18 is an enlarged view of the selected portion 18 in FIG. 2.

The broken lines shown in the drawings depict portions of the case for an electric screwdriver that form no part of the claimed design.

1 Claim, 18 Drawing Sheets
